O. M. REXINGER

WINDOW GRATING

Filed Dec. 28, 1926

FIG. 2.

Inventor;
Otto M. Rexinger,
per N.W. Carandall
Attorney.

UNITED STATES PATENT OFFICE.

OTTO M. REXINGER, OF BEVERLY HILLS, CALIFORNIA.

WINDOW GRATING.

Application filed December 28, 1926. Serial No. 157,565.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects 10 and advantages, other than those specifically mentioned, are included within its scope.

My invention relates to removable gratings for the protection of window openings and the like. Among its principal objects 15 are; first, to provide an expandable grating that may readily be inserted between the jambs of a window casing beneath or above a raised or lowered sash; second, to furnish facilities for locking the grating in position 20 to prevent its removal by unauthorized persons; third, to afford ready means for attaching canvas or other roller curtains on either or both sides of the grating at will; and, fourth, to supply a relatively simple 25 and inexpensive device adapted to function in the ways just stated.

My objects are attained in the manner illustrated in the accompanying drawing, in which—

30 Figure 1 is an elevation of a window opening with a portion of the window frame at the left partially broken away, and with my improved grating installed therein beneath a sash; and

35 Figure 2 is a horizontal section of the casing of the above window, taken on the line 2—2 of Fig. 1 and with my device shown in plan in operative relation thereto.

Similar reference numerals refer to similar parts throughout both views.

My grating comprises a pair of variably spaced upright side members 5, spanned by a series of spaced telescoping bars. The latter consist of outer tubes 6, and inner bars 45 7. Within each of the outer tubes is a helical compression spring, as shown at 8. These springs press against the inner ends of bars 7 and tend to expel them from tubes

6, and thus to force side members 5 apart. A cross bar 9 spans two of the tubes 6, and a 50 similar cross bar 10 spans the corresponding pair of bars 7. These cross bars serve as grab-holds whereby the side members of the grating may be brought nearer to each other when the grating is to be installed or 55 removed.

In the form of my invention selected for illustration the side members 5 are made of channel iron having a width only slightly less than the thickness of the window sash, 60 so as to be able to enter the sash runway of the window frame. The edges of the channel flanges preferably are dentated as at 11, to enable them to better engage jambs 12 of the window frame. At the tops of the side 65 members are brackets 13 adapted for supporting shade rollers when it is so desired. These brackets may be of any suitable and approved design and they may be placed either on the outside or inside of the grating, 70 or on both sides as shown.

A locking mechanism of suitable type is provided at 14, whereby the grating may be locked in its extended position in the window frame to prevent it being removed by 75 unauthorized persons.

The operation of my invention will be clearly apparent from the foregoing description when it is further stated that, to effectively protect a window opening thereby, all 80 that is necessary is to raise the sash 15 and put my grating below it in the sash runways, locking it in its extended position.

Having thus fully described my invention, I claim:

85 A device of the character described, comprising; a pair of variably spaced parallel side members; a plurality of spaced pairs of telescopic members connecting and aligning the side members; springs within the 90 outer telescopic members adapted for pushing the inner telescopic members outwardly to separate the side members; and means for locking the telescopic members in extended position.

OTTO M. REXINGER.
